UNITED STATES PATENT OFFICE.

PATRICK J. CLANCY, OF BOSTON, MASSACHUSETTS.

BOAT-RELEASING DEVICE.

1,314,947.

Specification of Letters Patent.

Patented Sept. 2, 1919.

Application filed March 22, 1918. Serial No. 223,920.

To all whom it may concern:

Be it known that I, PATRICK J. CLANCY, residing at Boston, in the county of Suffolk and State of Massachusetts, a citizen of the 5 United States, have invented a new and useful Improvement in Boat-Releasing Devices, of which the following is a full, clear, and exact description, reference being had to the accompanying drawings, forming a 10 part of this specification, in explaining its nature.

The present invention relates to that part of a boat's gear or tackle by which a ship's boats are lowered into the water alongside the ship and the release of the boats then effected, the device or devices comprising my 15 invention pertaining essentially to the immediate connections between the tackle and the boat and which permit of the manual release or disengagement of the boat from the 20 tackle as occasion requires.

It is among the objects of my invention to provide connections or devices of the above character which up to the time the 25 manual release of the boat is effected will act to positively hold or support the boat without possibility of disengagement; connections or devices permitting of the manual release or disengagement of the boat only 30 when the boat is properly launched; which permit only of a simultaneous release of the tackle from both ends of the boat with which the tackle ordinarily connects and which also permits of a positive clearing 35 of the boat from the tackle without possibility of reengagement after the manual operation for obtaining the release has once been effected.

The invention can best be seen and understood 40 by reference to the drawings in which—

Figure 1 is a plan of a boat equipped with the devices comprising the invention.

Fig. 2 is a longitudinal vertical section of 45 the boat showing the devices in side elevation.

Fig. 3 shows in side elevation one of the boat-releasing devices, the same being shown in enlarged detail.

Fig. 4 is a section of the same taken on the line 4—4 of Fig. 3.

Fig. 5 is a longitudinal vertical section of the complete device, and

Fig. 6 is a section of the device taken 55 on the line 6—6 of Fig. 5.

Referring to the drawings:—

1 represents the boat which it will be assumed is swung from a vessel (not shown) by means of tackle 2 hung from the usual davits (not shown) and connecting respectively with the opposite ends of the boat through the releasable connections 3 comprising my invention.

The connections or devices 3 are in the nature of couplings, each comprising a 65 socket-forming member 4 which is secured to the boat, a tongue-forming member 5 with which the tackle 2 connects, and a releasable latch or bolt 6 for locking together the combined members.

The socket-forming member 4 consists of a chambered fixture or casing preferably rectangular in form, the lower end of which is open and provided with outwardly-extending flanges 8 through which bolts 9 or other fastenings may extend by which the casing is secured to the boat. The top of the casing is closed excepting for an opening 10 which admits of the entry of the tongue 11 of the tongue-forming member 5. This 70 75 tongue comprises preferably an elongated rectangular plate and the opening 10 in the top of the casing is made just large enough to admit of the passage of the tongue.

The chamber of the casing forms a socket 80 within which the tongue is contained, the tongue entering to a point well within the chamber.

The tongue has normally a vertical disposition in relation to the casing. The relation between the tongue and the casing is also such that the tongue may be free to assume other than a vertical position in relation to the casing or turned to assume angular position with relation thereto. The 85 tongue will fulcrum or turn upon the edges to the opening 10 in the top of the casing, the top of the casing being cut away or beveled and the chamber of the casing being sufficiently large to admit of the turning of 90 the tongue. The socket-forming member is so placed upon the boat that the tongue, thus free to turn, will turn upon an axis extending substantially at right angles to the longitudinal line of the boat.

The tongue-forming member 5, as above pointed out, comprises preferably an elongated plate with which the tackle connects through a suitably-interposed ring 12 to which the tackle is secured and which in 100 105 110

turn passes through a hole or opening 13 formed in the top of the tongue-forming member. The extent of entry of the tongue into the socket-forming member is limited 5 or defined by shoulders 14 on the plate which engage the top of the socket-forming member at the opposite ends of the opening 10 within it.

The releasable latch or bolt 6 which locks 10 the two members together extends crosswise through the socket-forming member and through the tongue within it when the tongue is properly socketed within the member as above explained. The bolt is mounted 15 to slide within a tubular casing 16 threaded within an opening in one side of the socket-forming member and projecting outwardly therefrom at an angle normal to it. The end of the casing 16 is closed by a chamfered cap 17 threaded to fit thereon excepting 20 for a central opening in the cap through which the shank 18 of the bolt extends. The shank is made smaller than the head of the bolt proper 6 and between the bolt or head 25 and the cap, coiled around the shank of the bolt, is a spring 19 the tension of which maintains the bolt in a normal extended or locking position, permitting, however, of the retraction or withdrawal of the bolt upon 30 the compression of the spring.

A further arrangement is provided whereby the bolt may be maintained in a retract position upon its withdrawal for releasing the tongue. This comprises an auxiliary bolt or plunger 22 having an annular rib or collar 23 and a shank 24 carrying upon its end a handle or knob 25 for operating the bolt. The rib or collar 23 of the bolt is mounted to slide within a tubular casing 26 threaded into an opening formed 35 in the side of the tubular casing 16 adjacent the bolt 6. The end of the casing 26 is closed by a cap 27 threaded to fit upon it and provided with a central opening through 40 which the shank 24 extends. Coiled around the shank between the rib or collar 23 and the cap 27 is a spring 28 the tension of which maintains the auxiliary bolt in a normal extended or locking position, permitting, however, of its retraction or withdrawal by compression of the spring. The auxiliary bolt 22 is maintained by the spring 45 28 in constant lateral engagement with the bolt 6, the end of the auxiliary bolt extending 50 to lie within the slot 30 cut in the side of the bolt 6. At the forward end of the slot 30 the bolt 6 is provided with a socket 31 into which the auxiliary bolt, influenced by the tension of the spring backing it, fastens 55 automatically when the bolt 6 is withdrawn sufficiently to release the tongue, the auxiliary bolt then operating to hold the main bolt in its withdrawn or retracted position until release is obtained by a pull upon the 60 shank of the auxiliary bolt. When the aux-

iliary bolt is released the main bolt will be made to assume a locking position by the tension of the spring back of it. The auxiliary bolt will always slip into the socket 31 when the main bolt has been retracted inasmuch as the normal relationship is maintained between the two bolts by the slot in the main bolt into which the auxiliary bolt fits, the engagement between the sides of this slot and the auxiliary bolt preventing the 75 main bolt from turning within its casing and otherwise maintaining such normal relationship between the two bolts that the auxiliary bolt will always slip into its socket when the main bolt has been properly retracted for releasing the tongue.

Connecting with the shanks of the main bolts to the couplings, when arranged at the forward and rear ends of the boat, are ropes or connections 33, 34, respectively. These 80 ropes connect with the shanks through interposed shackles 35 which by their engagement with the caps 17 which form the ends of the casings through which the shanks extend, operate to define the extended position of the 85 bolts or such as will fairly and properly lock together the two parts of the coupling when the bolt is extended. From the respective shackles and ends of the shanks of the bolts the ropes or connections 33, 34, extend backward 90 toward the center of the boat around idler pulleys 36. Thence the lines or connections extend laterally toward one side of the boat around idler pulleys 37. Thence the lines or connections extend along the 95 side of the boat to a point about midway the boat where the ends of the ropes or connections both pass through a fixture 38 and the ends of the ropes beyond the fixture fasten together. The connected ends of the ropes 100 are provided with any suitable ring or handle 39 fastened to them.

With the above described arrangement it will first be observed that the connections or couplings between the tackle and the boat 110 are such as to offer a positive means of retention without possibility of accidental disengagement or separation of the parts of the coupling requiring the withdrawal of the main bolts, which can be effected only by 115 manual operation. The respective couplings may be released either separately or collectively by a pull upon the ropes or connections 33, 34. In no event, however, can either of these couplings be released as long as the weight of the boat comes upon the coupling inasmuch as the draw of the tongue and ensuing frictional resistance of the connected parts will prevent a withdrawal of the bolt. In other words, the coupling at 120 either end of the boat cannot be broken until the tackle connecting with such end of the boat is relieved of the strain upon it and which relief is obtained only by a proper launching of that end of the boat. The ar- 125 130

angement is also such that both of the main bolts for releasing the respective couplings can only be withdrawn simultaneously, that is, when pull is made upon the ring or handle 39. In other words, a cramping of either of the main bolts within its socket will prevent the main bolt to the other socket from being pulled. Consequently the bolts cannot be withdrawn and the couplings broken 10 until the boat has been properly launched and the tackle connecting with both ends of the boat relieved of all strain.

In the ordinary operation of the parts after the breaking of the couplings the 15 tongues to which the tackle is secured will pull away from the socket members. It might happen, however, that both couplings might be broken by the withdrawal of their respective main bolts and the tackle with the 20 tongue secured to it pull away from only one of the couplings. If then the pull on the bolt of the other disconnected coupling is not maintained this coupling might again become locked by the return of the bolt. To 25 prevent such possibility means are employed by which when the bolts are once withdrawn or retracted they are held in their withdrawn or retracted positions automatically by means of the auxiliary bolts, thereby preventing any possibility of the occurrence 30 just referred to. The arrangement whereby the tongues may be turned in their respective sockets after the withdrawal of the main bolts is to facilitate the withdrawal of the 35 tongues from their sockets after the withdrawal of the main bolts. In some cases the draft exerted by the tackle for pulling the tongues away from their sockets after the pulling of the main bolts might not be a vertical pull but at an angle, and to prevent 40 any possibility of the tongues binding within their sockets in such event a certain freedom of movement is afforded them as above explained.

Having thus fully described my invention, I claim and desire to secure by Letters Patent of the United States:—

1. The combination with a boat and its supporting tackle, of couplings securing said 50 tackle to the opposite ends of the boat, each

of said couplings comprising complementary separable parts attachable one to the boat and the other to the tackle, and a latch releasable by a pull connecting said parts, means for maintaining each of said latches 55 to occupy normally an engaging position, means whereby pull may be exerted upon the latches of the respective couplings for releasing the latches and whereby, also, said latches may be released simultaneously, and 60 means whereby said latches when released may automatically be held in an open position.

2. The combination with a boat and its supporting tackle, of couplings securing said 65 tackle to the opposite ends of the boat, each of said couplings comprising complementary tongue and socket members attachable one to the boat and the other to the tackle and separable one from the other by pull in a 70 substantial vertical direction, each of said couplings comprising, also, a latch extending transversely through said members and releasable by a pull thereon only when said members are relieved of strain tending to 75 separate the same, means for maintaining each of said latches to occupy normally an engaging position, means whereby pull may be exerted upon the latches of the respective couplings for releasing the latches and 80 whereby, also, said latches may be released simultaneously when the tongue and socket members of both couplings are relieved of strain thereon tending to separate the same, and means whereby said latches when released 85 may automatically be held in an open position.

3. A boat-releasing device comprising complementary tongue and socket forming members attachable, respectively, to parts to 90 be connected, a latch releasable by a pull carried by the socket-forming one of said members for connecting said members, means for maintaining said latch to occupy normally an engaging position, and means acting automatically to hold said latch in an open position when the latch is drawn, disconnecting said members.

PATRICK J. CLANCY.
